(57) **CLAIM**

The ornamental design for a canister portion, as shown and described.

DESCRIPTION

FIG. 1 is a front elevational view of a canister with the lid in an open position, showing our new design;

FIG. 2 is a front elevational view thereof, with the lid in a closed position;

FIG. 3 is a back elevational view thereof, with the lid in an open position;

FIG. 4 is a back elevational view thereof, with the lid in a closed position;

FIG. 5 is a left side elevational view thereof, with the lid in an open position;

FIG. 6 is a left side elevational view thereof, with the lid in a closed position;

FIG. 7 is a right side elevational view thereof, with the lid in an open position;

FIG. 8 is a right side elevational view thereof, with the lid in a closed position;

FIG. 9 is a top plan view thereof, with the lid in an open position;

FIG. 10 is a top plan view thereof, with the lid in a closed position;

FIG. 11 is a bottom plan view thereof, with the lid in an open position;

FIG. 12 is a bottom plan view thereof, with the lid in a closed position;

FIG. 13 is a top, front, right side isometric view thereof, with the lid in an open position;

FIG. 14 is a top, front, right side isometric view thereof, with the lid in a closed position;

FIG. 15 is a top, front, right side exploded view thereof, with the lid in an open position; and,

FIG. 16 is a top, front, right side exploded view thereof, with the lid in a closed position.

The broken lines are for purposes of illustrating unclaimed portions of the canister and form no part of the claimed design.

1 Claim, 16 Drawing Sheets
